OF NEW YORK, N. Y., A CORPORATION OF DELAWARE.

FIRE-EXTINGUISHING SYSTEM.

1,421,433.

Specification of Letters Patent. Patented July 4, 1922.

Application filed October 1, 1919. Serial No. 327,759.

To all whom it may concern:

Be it known that I, FRANK A. EPPS, a citizen of the United States, and resident of New York city, in the county of New York and State of New York, have invented certain new and useful Improvements in Fire-Extinguishing Systems, of which the following is a specification.

This invention relates to fire extinguishing systems and particularly to systems of the dry pipe type in which a pump is used to supply the extinguishing medium to the distributing point.

In certain types of fire extinguishing systems it has been the practice to utilize a pump to provide the pressure under which the extinguishing fluid is propelled through the system in case of fire, the pump normally being inactive, with means operated in the presence of a fire to start the pump. This type of system is particularly valuable when the foam-producing type of extinguishing medium is used, as the component liquids used to produce the foam are ordinarily maintained in separate tanks, and it is desirable to use a pump to supply the liquids under pressure in case of fire in order to avoid maintaining the tanks under pressure and to permit the replenishing of the liquids therein during the progress of a fire. It will be apparent, however, that my system is not necessarily limited to the foam-producing type of extinguishing system.

It is likewise highly desirable to maintain the pipes of such a system free from the liquid except in case of emergency, particularly to avoid freezing in the pipes and corrosion thereof by the liquid. This result is ordinarily obtained by filling the pipes with compressed air and introducing a check valve, ordinarily of the differential type generally known as a "dry pipe valve," the use of which permits a relatively low air pressure in the pipes to prevent the flow of liquid under considerably greater pressure. When pumps have been utilized, however, the fact that the liquid is not under pressure has permitted the use of an ordinary check valve at the point of contact between the compressed air in the pipes and the liquid supply. While this may be located either between the source of liquid supply and the pump or between the pump and the distributing system the former location necessarily fills the pump with compressed

air, while the latter subjects the pump to the continued corrosive action of the liquid. It is extremely difficult to pack all stuffing boxes and similar bearings for moving parts of the pump passing from the inside to the outside thereof, in such a way that air cannot escape; and where the check valve has been located between the pump and the source of liquid supply constant leakage of the compressed air through the pump has resulted. On the other hand, where liquids containing acid or other corrosive chemicals are used in the system, as is the case with foam producing liquids, it is practically necessary to keep the pump free from the liquid when standing idle; but regardless of the liquid used, this arrangement is highly desirable, due to the expense of replacing pump parts and linings eroded by the liquid.

These two difficulties have been avoided by providing a system utilizing a source of liquid supply under pressure insufficient to supply the liquid at the distributing point; a pump for providing the pressure; a distributing system filled with compressed air; and means for maintaining the pump free from both the liquid and the compressed air.

The system has also been arranged so that the drop in pressure of the compressed air caused by the opening of a distributing valve or vent in the presence of fire will operate both to start the pump and to bring the extinguishing liquid to the pump.

There also has been provided means for accelerating the delivery of the extinguishing fluid to the pump when a sudden drop in pressure in the compressed air occurs, an operation which is highly desirable when a differential valve is used for the purpose of restraining the liquid, under the common practice. It has been found that with such a differential valve, which operates under a substantial margin of safety, a considerable drop in air pressure is necessary to release the valve and permit the flow of liquid. When only a relatively small vent has been opened in the presence of fire conditions the drop in air pressure is necessarily gradual and the time elapsing between the opening of the vent and the release of a liquid by operation of the valve may be so great as to be a serious factor.

This means for accelerating the action of the check valve, which may be called an ac-

110

celerator, may be omitted under proper conditions as to pressure of the liquid, pressure in the air system, and size of distributing vent, as it is not essential to the operation of the system. In its preferred form it is operated by the rate of drop in pressure and not by the extent of drop, which prevents its operation in the presence of the slow leakage incident to most systems, but bringing the accelerator into operation in the presence of fire conditions almost immediately, considerably before the pressure of the compressed air has dropped to the point of opening the differential valve.

The invention has been illustrated as applied to the two solution type of fire extinguishing medium, as it is particularly adapted for use in a system in which two liquids are mixed at the distributing point to produce the fire extinguishing medium, which preferably is of the foam type. For this purpose a complete duplex system is disclosed, both parts of the system being exactly the same except for the provision of a single means for starting the pumps and common distributing elements; but it is apparent that this is merely illustrative, as obviously many parts of the two systems might be used in common, especially when other types of distributing elements are employed.

Other objects and advantages of this invention will be apparent from the following description taken in connection with the accompanying drawing in which:

Figure 1 is a partly diagrammatic view of a duplex system, the differential valves being shown in section and,

Figure 2 is a detail side view of the accelerator, the working parts being shown in vertical section,

Fig. 3 is a sectional view of the check valve.

As the two distributing systems are practically the same, only one will be described in detail. Each system includes a source of supply for an extinguishing fluid, which may be a tank 10, as indicated in fragmentary view in Fig. 1. The fluid is conveyed from the source to pump 11 through a pipe 12 which is normally closed by a check valve 13, pipe 14 connecting the check valve and the pump 11 and conveying the fluid to the pump when the check valve is opened. The riser 15 conducts the fluid from the pump to the outlet. While the sprinkler-head type of distributing system is illustrated it will be apparent that this is entirely incidental as the system may be used with equal effectiveness with other types of distributing means such as the large distributing head used on oil tanks or in connection with mixers attached to hose lines or the like. In the type illustrated, riser 15 is provided with one or more lateral pipe lines 16 carry-

ing sprinkler heads 17, and where the system is used with an extinguishing medium composed of two liquids mixed at the distributing point, parallel adjacent lateral lines 16 are preferably provided, each line being connected to a different riser 15, and both being preferably connected to each sprinkler-head 17, or other distributing element, as by connection 18.

Means is provided for preventing the entrance of the extinguishing fluid into riser 15, which preferably is accomplished by filling the riser and lateral pipes 16 with compressed air in any way, as by connecting them with an air pump (not shown) adapted to maintain the air in the riser and lateral lines at a predetermined pressure. Means is provided for preventing the entrance of the compressed air into pump 11, said means preferably consisting of a check valve 19 which may be located immediately adjacent the pump. This valve may be of any desired type but it is desirable to employ the water sealed form of valve to prevent leakage of air.

Means is provided for preventing the extinguishing fluid from entering the pump 11, said means preferably consisting of valve 13 located at the junction between pipes 12 and 14 and serving to close pipe 12 against the normal pressure of the fluid. This valve is illustrated as being of the differential type, preferably consisting of what is ordinarily termed a "dry pipe valve" and is normally held in closed position to restrain the flow of the fluid by means of the pressure of the air in the distributing system, which is connected to the valve through pipe 20 practically constituting a bypass around the pump. Check valve 13 preferably includes two valve flaps, an upper flap 21 being hinged to the valve casing and serving to prevent the passage of the compressed air from pipe 20 into pipe 14, thus constituting means for preventing the air pressure from reaching the pump on the suction side. A second valve flap 22 is provided for closing pipe 12 and is preferably connected to flap 21, being substantially smaller in size than said flap 21 so that a relatively small air pressure bearing against the upper side of valve flap 21 will serve to maintain pipe 12 closed under considerably greater pressure of the extinguishing fluid. If desired a check valve 23 may also be inserted in pipe 20 adapted to prevent the exhausting of the air pressure in the distributing system upon opening or removing any of the parts connected to the check valve and associated mechanism and also to prevent the circulation of the extinguishing medium through pipe 20 from the pressure side to the suction side of the pump when the latter is in operation. Check valve 23 if used is provided with a small vent which permits the air to bleed

from riser 15 into the lower part of pipe 20, so that the pressure in the distributing system and in pipe 20 will be equalized under normal conditions. Means for starting the 5 pump 11 is provided preferably operated by a drop in air pressure in the distributing vent under fire conditions. The ordinary type of pressure-controlled starter as for example, the Clarke starter, shown in the 10 patent to Lufkin, No. 578,606, such starter being diagrammatically indicated at 24 and is preferably connected to pipe 20. It will be apparent that whether a single or duplex system is used only one automatic starting 15 element 24 will be needed.

A drain 25 is preferably provided for maintaining pipe 14 clear of liquid such as leakage past valve flap 22.

The operation of the system as so far described will be apparent; but a short summary will be given. Under normal conditions the distributing system including riser 15, laterals 16, and pipes 20, are filled with air under any desired pressure, which may be approximately fifty pounds. Extinguishing fluid may be contained in tank 10 and the pressure thereof at valve 13 is ordinarily merely that produced by gravity; but the normal pressure may be augmented in any preferred way within the scope of my invention. Differential valve 13 is so proportioned that the air pressure in the distributing system is sufficient to prevent the flow of the fluid into pipe 14. Upon the occurrence of a fire a distributing vent such as sprinkler-head 17 is opened, and the escape of compressed air results in a drop in air pressure communicated through riser 15 to pipe 20, whereupon check valve 23 opens, and starter 24 is actuated, starting the pump. At the same time the reduction in pressure behind valve flap 21 reaches a point where the pressure of the liquid in pipe 12 raises valve flap 22 and the fluid flows directly to the pump and through riser 15 to the distributing system, check valve 19 being released by the pressure from the pump.

50 While the system as described is operative and complete in itself, means may be provided if desired for accelerating the action of check valve 18 to supply the fluid to the pump at the earliest possible moment. This preferably consists of means for rapidly opening a bypass between pipe 20 and pipe 55 14 so as to equalize the pressure on both sides of valve flap 21, under which conditions any slight pressure of the liquid in pipe 12 will be sufficient to cause the valve to open, permitting the fluid to flow direct 60 to the pump.

I have disclosed one form of mechanism for opening the bypass upon a sudden drop in pressure; but any desired mechanism may be substituted; as the form disclosed 65 comprises no part of my invention.

As shown best in Figure 2 the accelerator mechanism preferably includes a lower chamber 26 connected to the compressed air system, as by pipe 27 opening into pipe 20. The upper chamber 28 is likewise connected to the compressed air system as by a pipe 29 which is shown as communicating directly with pipe 27. Located in pipe 29 is a partition 30 which is adapted to permit the passage of air through said pipe only at a relatively slow rate, the partition being of any desired form, such as a diaphragm, flap or gate valve, or a porous or perforated partition, alundum being suitable for the purpose. A bypass 31 containing a hand valve 32 may be provided for putting the system into operation, but normally remains closed. The lower chamber 26 is connected to pipe 14 by pipe 33, the upper end of which is closed by valve 34. A flexible diaphragm 35 is mounted between chambers 26 and 28 and in contact with a slidably mounted plunger 36. A weight 37 is supported by an arm 38 pivoted to the casing and having a toe 39 adjacent valve 34. 90

The operation of the accelerator is as follows. The pressure in the distributing system is communicated through pipes 27 and 29 to chambers 26 and 28 which normally are under equal pressure. A change in pressure in pipe 20 will be immediately transmitted to chamber 26, but can only be communicated to chamber 28 by the escape of air therefrom through partition 30. As this process is relatively slow, a difference in pressure between chambers 26 and 28 is created, the extent of which is determined by the rate of change in the pressure in pipe 20. If the change is caused by leakage or other minor reasons no effect will be produced, as the change in pressure would be too gradual; but upon the occurrence of a fire and the consequent relatively rapid drop in pressure the higher pressure in chamber 28 forces diaphragm 35 inward, sliding 110 plunger 36 against weight 37. The weight is normally balanced upon its pivot, and may rest on the top of valve 34; but when shifted by plunger 36 it falls backward, raising toe 39, which opens valve 34, providing a direct connection or bypass between the distributing system and pipe 14 and equalizing the pressure on both sides of the valve flap 21. 115

If a duplex system is employed it will be 120 apparent that, although an accelerator has been shown as used with each part of the system, that both parts of the system need not be supplied with individual accelerators.

While I have described the preferred form 125 of my invention and indicated certain variations thereof, it will be apparent that many other changes and substitutions may be made within the scope of my invention as set forth in this specification. 130

I claim:

1. In a fire extinguishing system, in combination, a source of supply for the extinguishing medium, means for conducting the medium to a distributing point, means connected to the source of supply and to the conducting means for forcing the medium from the source of supply through the conducting means, a fluid filling said conducting means, means for preventing the flow of the fluid into the forcing means, and means for preventing the flow of the medium into the forcing means.
2. In a fire extinguishing system, in combination, a source of supply for the extinguishing medium, means for conducting the medium to a distributing point, means connected to the source of supply and to the conducting means for forcing the medium from the source of supply through the conducting means, compressed air filling said conducting means, means for preventing the flow of the compressed air into the forcing means, and means for preventing the flow of the medium into the forcing means.
3. In a fire extinguishing system, in combination, a source of supply for the extinguishing medium, means for conducting the medium to a distributing point, means connected to the source of supply and to the conducting means for forcing the medium from the source of supply through the conducting means, compressed air filling said conducting means, means for preventing the flow of the compressed air into the forcing means, and means for preventing the flow of the medium into the forcing means released by a reduction in pressure of the compressed air to permit the flow of the medium from the source to the forcing means.
4. In a fire extinguishing system, in combination, a source of supply for the extinguishing medium, a pump associated therewith, means for conducting the medium from the pump to a distribution point, a fluid filling the conducting means, means for preventing the flow of the fluid into the pump, and means for preventing the flow of the medium into the pump.
5. In a fire extinguishing system, in combination, a source of supply for the extinguishing medium, a pump associated therewith, means for conducting the medium from the pump to a distribution point, a fluid filling the conducting means, means for preventing the flow of the fluid into the pump, and means, actuated by the pressure of said fluid, for preventing the flow of the medium into the pump.
6. In a fire extinguishing system, in combination, a source of supply for the extinguishing medium, a pump associated therewith, means for conducting the medium from the pump to a distribution point, compressed air filling the conducting means,
- means for preventing the flow of the compressed air into the pump, and means for preventing the flow of the medium into the pump.
7. In a fire extinguishing system, in combination, a source of supply for the extinguishing medium, a pump associated therewith, means for conducting the medium from the pump to a distribution point, compressed air filling the conducting means, means for preventing the flow of the compressed air into the pump, and means, actuated by the pressure of said compressed air for preventing the flow of the medium into the pump.
8. In a fire extinguishing system, in combination, a source of supply for the extinguishing medium, a pump associated therewith, means for conducting the medium from the pump to a distribution point, compressed air filling the conducting means, means for preventing the flow of the compressed air into the pump, and means for preventing the flow of the medium into the pump automatically released in the presence of fire conditions to permit the medium to flow to the pump.
9. In a fire extinguishing system, in combination, a source of supply for the extinguishing medium, a pump associated therewith, means for conducting the medium from the pump to a distribution point, compressed air filling the conducting means, means for preventing the flow of the compressed air into the pump, and means for preventing the flow of the medium into the pump automatically released, by decrease in pressure of the compressed air, in the presence of fire conditions to permit the medium to flow to the pump.
10. In a fire extinguishing system, in combination, a pump, a source of supply containing a fire extinguishing medium normally tending to flow to the pump, means for conducting the medium from the pump to a distribution point, compressed air normally filling said conducting means, a valve for preventing the flow of the medium from the source to the pump, adapted to be released by a decrease in pressure of the compressed air to permit said flow, and a check valve for preventing the compressed air from entering the pump.
11. In a fire extinguishing system, in combination, a source of supply for the extinguishing medium, a pump associated therewith, means for conducting the medium from the pump to a distribution point, means for starting the pump, means for preventing the flow of the medium into the pump, and means operable in the presence of fire for automatically simultaneously actuating the pump starting means and releasing the flow preventing means.
12. In a fire extinguishing system, in com-

- combination, a source of supply for the extinguishing medium, a pump associated therewith, means for conducting the medium from the pump to a distribution point, compressed air normally filling said conducting means, means actuated by a decrease in pressure of the compressed air, for automatically starting the pump, and means for preventing the flow of the medium from the source of supply to the pump, adapted to be released by the reduction in pressure of the compressed air in the conducting means, to permit said flow.
13. In a fire extinguishing system, in combination, a source of supply for the extinguishing medium, means for conducting the medium to a distribution point, means connected to the source of supply and to the conducting means for forcing the medium from the source of supply through the conducting means, compressed air normally filling the conducting means, means for preventing the flow of the medium from the source of supply to the forcing means, and means for releasing said flow preventing means, operated in the presence of a reduction in the pressure of the compressed air at a rate greater than a predetermined minimum rate of decrease.
14. In a fire extinguishing system, in combination, a source of supply for the extinguishing medium, a pump associated therewith, means for conducting the medium from the pump to a distribution point, compressed air normally filling said conducting means, means for preventing the flow of the medium to the pump, and means, actuated to release said flow preventing means in the presence of a decrease in the pressure of the compressed air at a rate greater than a predetermined minimum rate of decrease.
15. In a fire extinguishing system, in combination, a source of supply containing a fire extinguishing medium, a pump associated therewith, means for conducting the medium from the pump to a distribution point, compressed air normally filling said conducting means, a valve controlled by the pressure of said compressed air to prevent the flow of the medium from the source to the pump, and means, operative in the presence of a decrease in pressure of the compressed air at a rate greater than a predetermined minimum rate, to release the effective pressure of the compressed air upon the valve, permitting it to open and allow the medium to flow to the pump.
16. In a fire extinguishing system of the two-solution foam-producing type, a separate source of supply for each solution, means for conducting each solution separately to a common point of distribution, compressed air normally filling said conducting means, means connected to the source of supply and to the conducting means for forcing each solution from its source to the distributing point, means for normally preventing the flow of each solution from its source to its forcing means, released in the presence of a reduction in pressure of the compressed air to permit the solution to flow to the forcing means, and means connected to the conducting means of one of said solutions and actuated by a decrease in the pressure of the compressed air therein, to render said forcing means operative.
17. In a fire extinguishing system of the two-solution foam-producing type, a separate source of supply for each solution, means for conducting each solution separately to a common point of distribution, compressed air normally filling said conducting means, pumping means connected to the source of supply and to the conducting means for forcing the solutions from their sources to the distributing point, means for maintaining the pumping means free from compressed air, means for normally preventing the flow of each solution from its source to the pumping means, and means for simultaneously releasing said flow preventing means to permit both solutions to flow to the pumping means.
18. In a fire extinguishing system of the two-solution foam-producing type, a separate source of supply for each solution, means for conducting each solution separately to a common point of distribution, compressed air normally filling said conducting means, pumping means connected to the source of supply and to the conducting means for forcing each solution from its source to the distributing point, means for normally preventing the flow of each solution from its source to the pumping means, controlled by the pressure of the compressed air and adapted to be released in the presence of a simultaneous reduction in pressure of said air in the conducting means for both solutions.
19. In a fire extinguishing system of the two-solution foam-producing type, a separate source of supply for each solution, means for conducting each solution separately to a common point of distribution, compressed air normally filling said conducting means, pumping means connected to the source of supply and to the conducting means for forcing each solution from its source to the distributing point, means for normally preventing the flow of each solution from its source to the pumping means, controlled by the pressure of the compressed air in the conducting means, and means for simultaneously automatically releasing said preventing means in the presence of fire conditions to permit the flow of both solutions simultaneously to the pumping means.

20. In a fire extinguishing system of the two-solution foam-producing type, a separate source of supply for each solution, means for conducting each solution separately 5 to a common point of distribution, compressed air normally filling said conducting means, pumping means connected to the source of supply and to the conducting means for forcing each solution from its 10 source to the distributing point, means for normally preventing the flow of each solution from its source to the pumping means controlled by the pressure of the compressed air in the conducting means and adapted to 15 be released by a decrease in pressure of the compressed air, and means, located adjacent the distributing point, adapted to open a vent in the conducting means for both solutions simultaneously so as to decrease the 20 air pressure and simultaneously start the flow of both solutions to the pumping means.
21. In a fire extinguishing system of the two-solution foam-producing type, a separate source of supply for each solution, means for conducting each solution separately 25 to a common point of distribution, compressed air normally filling said conducting means, pumping means connected to the source of supply and to the conducting means for forcing each solution from its 30 source to the distributing point, means for normally preventing the flow of each solution from its source to the pumping means, means for starting the pumping means, and means operable in the presence of fire for simultaneously automatically releasing said 35 preventing means for both solutions, and actuating said pump starting means.

Signed at New York, in the county of New York, and State of New York, this 30th day of Sept., A. D. 1919.

FRANK A. EPPS.
